UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

INSEAM-SHOE-SEWING MACHINE.

Application filed September 14, 1918. Serial No. 254,104.

To all whom it may concern:

Be it known that I, ALFRED B. FOWLER, a citizen of the United States, residing at Beverly, in the county of Essex and State 5 of Massachusetts, have invented certain new and useful Improvements in Inseam-Shoe-Sewing Machines; and I do hereby declare the following to be a full, clear, and exact description of the invention, such as will 10 enable others skilled in the art to which it appertains to make and use the same.

The present invention relates to inseam shoe sewing machines and is intended primarily as an improvement on that class of 15 inseam sewing machines which form a chain stitch and which are provided with a curved hook needle entering the shoe from the outside, and with a stitch setting take-up operating to pull the last formed loop tightly 20 around the shank of the needle while the needle is in the work. An example of this class of machine is the well known Goodyear welt and turn shoe sewing machine, the construction and mode of operation 25 of which is disclosed with substantial accuracy in the patent to French and Meyer, No. 412,704. As will be obvious to those skilled in the art, however, certain features of the present invention are equally applicable 30 to other types of inseam shoe sewing machines, and it is to be understood that, except as defined in the claims, the several features of the present invention are not limited to use in any particular type of inseam 35 sewing machine.

The several features of the present invention will be understood from the following detailed description and the accompanying drawings, in which Figure 1 is a front elevation 40 of a shoe sewing machine embodying the features of the present invention in their preferred form; Fig. 2 is a side elevation looking from the left, partly in section and with a portion of the casing removed; Fig. 3 is a sectional elevation looking 45 from the right, and taken on a plane just to the right of the needle segment; Fig. 4 is a plan view partly in section of a portion of the machine; Fig. 5 is an enlarged 50 sectional elevation of a portion of the mechanism shown in Fig. 3; Fig. 6 is a side elevation looking from the right partly in section and with the casing removed; Fig.

7 is an enlarged sectional side elevation of a portion of the mechanism shown in Fig. 55 2; Fig. 8 is a view showing the thread cutter and holder and the actuating devices for the same in front elevation and certain other parts in section; Fig. 9 is a detail sectional view on the line 9—9 of Fig. 8, looking 60 in the direction of the arrows; Fig. 10 is a detail view in front elevation of the actuating devices for the thread cutter and holder; Fig. 11 is a detail plan view partly 65 in section on the line 11—11 of Fig. 10, showing the looper actuating mechanism, and the thread cutting and holding device in position to engage the thread; Fig. 12 is a detail view in substantially vertical section 70 on the line 12—12 of Fig. 10, looking 75 in the direction of the arrows; Fig. 13 is a detail view in horizontal section of the clutch mechanism through which the thread cutter and holder are actuated; Fig. 14 is a detail view in vertical section on the line 75 14—14 of Fig. 13, looking in the direction of the arrows; Fig. 15 is a detail plan view partly in section of the actuating devices for the awl, needle and thread finger; Fig. 16 is a detail plan view of the channel closing finger, the back gage and back rest and the actuating devices therefor; Fig. 17 is a detail plan view of the back rest and the locking devices for the back rest and 80 back gage; Fig. 18 is a detail sectional elevation of the back rest and said locking devices; Fig. 19 is a detail vertical section 85 on the line 19—19 of Fig. 18 looking in the direction of the arrow; Fig. 20 is a detail vertical section on the line 20—20 of 90 Fig. 18 looking in the direction of the arrow; Fig. 21 is a vertical transverse section through the stop mechanism taken in a plane passing through the axis of the main driving shaft; and Fig. 22 is a longitudinal vertical section taken on the line 95 22—22 of Fig. 21, and looking in the direction of the arrows.

The machine illustrated in the drawings is provided with an awl or feed point, a 100 curved hook needle, a needle guide, a looper, a thread arm, a take-up, an auxiliary take-up, a channel guide, a back gage, a back rest, and a tension device, all having the same general function and mode of operation except as hereinafter described as the 105

corresponding parts of the well-known Goodyear inseam sewing machine, disclosed in Patent No. 412,704.

The awl or feed point 1 is secured on the awl segment 2 pivoted on a stud 3 which is mounted in the feed slide of the machine. The awl segment is actuated by means of a cam lever 4 operated by a cam on the main shaft, said cam lever being pivoted on a rod or stud 5 secured in the lower part of the head of the machine. A connecting link 6 connects the cam lever 4 and the awl segment 2, said link 6 being connected to the cam lever 4 by a ball pivot connection 7, and to the awl segment 2 by a similar ball pivot connection 8.

The needle is indicated at 9 and is secured in the needle segment 10 which is fast on a hollow shaft 11 through which passes a shaft 12. Pivotedly connected to the needle segment at 13 is a link 14, which is also pivotedly connected at 15 to the cam lever 4 which actuates the awl. The cam lever 4 thus gives an oscillating motion to both the needle and the awl, the needle being retracted from the work as the awl is advanced toward the work and vice versa.

When the awl is moved laterally to feed the work, the actuating link 6 is swung about its rear end as a pivot, the forward end of the link moving in the arc of a circle, the center of which is at the rear end of the link. This swinging movement of the link tends to move the awl segment forward so as to give the awl an additional work-penetrating movement. To prevent such additional forward movement of the awl, the cam which operates the needle and awl-actuating lever is so formed that the lever is moved rearwardly slightly during the feeding movement of the awl. This rearward movement of the actuating lever slightly advances the needle during the feeding movement of the awl while maintaining the point of the awl stationary with relation to the work.

Formed integral with the shaft 12 which passes through the hollow shaft 11 is the needle guide 16. Fixed on the other end of said shaft is an upstanding arm 17. This arm has in its upper end a slot 18 in which engages a pin 19 which is mounted on the forward end of a lever 20 fulcrumed at 21 on the machine frame. The rear end of the lever 20 has rotatably mounted thereon a roll 22 cooperating with a cam groove 23 formed in the upper arm of a lever 24 which is fulcrumed on a stud 25 projecting from the machine frame. Pivotedly connected at 26 to a downwardly extending arm of the lever 24 is a short connecting link 27, extending forwardly and pivotedly connected at 28 to the upper end of the cam lever 4 on the side of said lever opposite to that on which the link 14 connected to the needle segment is pivoted. By means of the above connec-

tions the cam lever 4 which oscillates the needle and awl segments, as above described, also oscillates the needle guide.

The lever 24 has on the side opposite to that on which the cam groove 23 is formed a cam groove 29 which cooperates with a roll 30 to give the thread arm the vibratory movements hereinafter described. On one end of a rock shaft 31 mounted for rotation in the machine frame is an arm 32, to which is secured the thread arm 34. Secured to the other end of said rock shaft 31 and extending upwardly therefrom is an arm 35 having pivotally connected to its upper end at 36 a short connecting link 37 pivotally connected at 38 to the forward end of a sliding bar 39. The roll 30 is mounted upon the sliding bar 39 and thus the bar is reciprocated from the cam groove 29 and roll 30 and through the connections above described actuates the thread arm.

The looper which lays the thread in the barb of the needle is indicated at 41 and is secured at the right end of a rod 42 so as to be capable of adjustment vertically by a key connection 43 and clamping bolt passing through a slot in the looper and screwing into the rod. This rod 42 is mounted to slide in a bearing or slideway 44, which is secured in a hub 45 journaled for rotation in the forward end of a slide rod 46. To the opposite end of the slide rod 42 there is pivotally connected an arm 47 of a bell-crank lever, the other arm 48 of which is vertically offset from arm 47 as shown in Fig. 7 of the drawings. Integral with the two arms of the bell-crank lever and extending between them is a vertically extending rod 49 journaled to rotate in a bearing 50 located in a bracket projecting from the main frame. Connected to the end of the arm 48 of the bell-crank lever by a ball pivot connection 51 is a link 52 extending rearwardly in the machine to a cam lever 53 pivoted on shaft 5 and operated by one of the operating cams on the main shaft of the machine. Said link 52 is connected to the upper end of the cam lever 53 by a ball-pivot connection 54, and means is provided for adjusting the length of the link 52 consisting of a turn-buckle 55 having right and left threaded engagement with the end portions of the link 52. The slide 46, above referred to, is mounted to have sliding motion backwardly and forwardly in the bracket which supports the bell-crank lever 47-48. This slide 46 at its rear end has an offset portion forming a projection 56 extending toward the left (Figs. 7 and 11) and connected to the projection by a ball pivot connection 57 is a link 58 connected at its rear end by another ball pivot connection 59 to the upper end of a cam lever 60 pivoted on shaft 5 and vibrated backwardly and forwardly by a cam on the main shaft. The link 58 is pro-

- vided with means for adjusting its length similar to the mechanism provided to adjust the length of link 52, and by adjusting the length of said links 52 and 58 the position 5 of the looper relative to the needle may be varied as desired. The combined action of these devices for giving motion to the looper causes the looper to move about the needle as hereinafter described.
- 10 It will be seen from an inspection of Fig. 11 that the thread handling devices of the machine illustrated in the drawings are arranged and actuated to form a chain stitch the loop of which is twisted through a complete turn. This form of stitch is highly desirable, especially in shoe work, since the twisted loops form a narrow seam lying closely against the material, and having the appearance of a single cord, and also effectively resist any tendency of the stitches to become loose. To form this twisted loop chain stitch the thread arm, in measuring off thread between the work and the needle, is given a movement outwardly toward the center line of the shoe, and the looper, in encircling the needle, is passed first across the plane of the needle outside of the circle of the needle, then across the plane of the needle inside of the circle of the needle, and finally again across the plane of the needle outside of the circle of the needle to lay the thread in the needle hook. When the needle retracts a twist is formed in the needle loop by reason of the fact that the thread leads from the work to the outside of the needle and completely encircles the needle before entering the hook. The outward movement given to the thread arm causes the thread to be held in such a position that the needle can be threaded in the desired manner and also this movement of the thread arm measures the thread accurately and without any liability of injury to the channel flap of the shoe sole.
- 45 The main take-up consists of a thread truck 62 mounted on the upper and forward end of a slide 63, which slides at an angle to the horizontal in a slideway formed between the machine frame and two plates 64 and 50 65 secured thereto. The slide 63 is given a reciprocatory sliding motion by means of a cam lever 66 connected to the slide by means of a link 67, said link being pivotally connected to the upper end of the cam lever and the lower end of the slide. The thread passes from the main take-up over a thread-truck 68 which acts as a guide for the thread and which is mounted for rotation on a stud 69 on which the feed slide or carriage, to be hereinafter described, slides. From the thread-truck 68 the thread passes over a thread-truck 70 which forms a part of an auxiliary take-up and thence through the looper.
- 60 The auxiliary take-up comprises a thread-truck 70 mounted on the forward end of an arm 71 which is pivoted on the stud 69. The arm 71 is acted upon by a spring 72, one end of which is secured in a hole in the arm 71 and the other end to a screw 75. The spring 72 tends to raise the arm until a projection 73 on the arm abuts against the lower end of an abutment screw 74, which may be adjusted and locked in any desired position 70 of adjustment by a lock-nut. The tension of the spring 72 may be adjusted as desired 75 by raising or lowering the adjusting screw 75, lock-nuts being provided for locking screw 75 in any desired position of adjustment.
- 75 The thread handling devices of the machine illustrated in the drawing are so arranged and operated that the main takeup acts to exert a stitch setting strain on the seam and draw off thread for the next loop from the tension wheel when the needle is in its forward position and extending through the work. The main take-up then falls during the thread measuring movement of the thread arm, during the looping movement of the looper and during the retracting movement of the needle. As the needle reaches the limit of its retracting movement it exerts a pull on the thread to tighten the preceding loop, such pull moving the auxiliary take-up arm 71 away from the abutment screw 74 and placing the auxiliary tension spring 72 under tension. To render the action of the main take-up, the auxiliary take-up and the needle certain, reliable and uniform under all conditions of sewing, means are provided in the machine illustrated in the drawings which ensure that the pull exerted upon the thread by the needle as it reaches the limit of its backward movement shall always be against the resistance offered by the auxiliary tension spring 72 and not against the resistance offered by the tension wheel 151. To secure this result the main take-up slide 63 is provided with a cam plate 76 having an inclined cam surface 77 and an extended raised surface 78 to cooperate with a pin 79 projecting from the rear end of the auxiliary take-up arm 71. The surface 78 of the cam plate 76 acts as a stop to engage the pin 79 and limit the movement of the auxiliary take-up during the action of the main take-up in setting the stitch, while the surface 77 acts to positively move the auxiliary take-up in case the strain on the thread during the first portion of the take-up movement of the main take-up moves the auxiliary take-up so as to bring the pin 79 into the path of said surface. During the last portion of the take-up action of the main take-up, therefore, the auxiliary take-up is practically locked in a position in which the projection 73 on the arm of the auxiliary take-up is nearly in contact with the abutment screw 74. As the main take-up moves to give up 125
- 130

4

thread, however, the surface 78 of the cam plate moves away from the path of the pin 79, leaving the auxiliary take-up free to be moved against the tension of the spring 5 72 so that when the needle exerts a pull on the thread at the end of its retracting movement, the auxiliary take-up can yield to the required extent without bringing up against a positive stop so as to cause any strain to 10 be exerted on the thread in addition to that caused by the spring 72 of the auxiliary take-up.

The slight advancing movement which is given to the needle during the feeding movement of the awl, referred to in the description of the awl actuating mechanism, tends to slacken the needle loop so as to relieve the strain on the needle and work during the feed. To enable the feeding movement of 20 the work to take place with substantially no interference whatever on account of the strain exerted by the thread, the take-up of the machine illustrated in the drawings is given a thread delivering movement during or just prior to the feeding of the shoe, which movement preferably is sufficient to allow the auxiliary take-up arm to be moved by its spring against the stop screw 74.

The machine herein disclosed is provided 30 with a channel closing finger which operates to press the channel flap down over the stitches of the seam as the sewing operation progresses. The channel closing finger is indicated at 80 and is secured to one end of a stud 81 pivotally mounted in the frame 35 of the machine. Secured to the other end of the stud 81 (see Figs. 7 and 16) is an arm 82 extending toward the rear of the machine and normally drawn upwardly by a tension 40 spring, 83, one end of which is secured to a pin on the machine frame and the other end to the rear end of the arm 82. This spring, tends to hold the channel closing finger down against the channel flap. The 45 upward movement of the arm 82 is limited by an abutment screw 84 adjustably secured to said arm and adapted to engage with a fixed abutment on the machine frame. This abutment screw may be adjusted as desired 50 and locked in position by means of a lock-nut 85.

The channel closing finger is raised from engagement with the channel flap during each stitch forming cycle and is also raised 55 whenever the machine is stopped to remove a sewed slice. To raise the finger when the machine is stopped there is secured to a rod 86, (Figs. 7 and 16) operated from the starting and stopping treadle, a collar 87. As 60 the collar 87 rises its upper surface engages the end of a rearwardly extended arm 88 of a lever fulcrumed on a pin 89 screwed into the machine frame. A forwardly extending arm 90 of said lever is formed as a cam and 65 overlies the arm 82. This cam is so designed

that when the arm 88 is rising, the highest part of the cam is brought into engagement with the arm 82, depressing said arm and consequently raising the channel closing finger 80 to a position out of engagement 70 with the channel flap. In such position the channel closing finger does not interfere with the removal of the shoe from the machine.

While the needle is in the work it is desirable to lift the channel closing finger out 75 of engagement with the channel flap so that said finger may be mounted close to the needle and yet not hold the channel flap in a position to interfere with the stitch forming and setting operations. To this end, the 80 channel closing finger is provided with a rearwardly extending arm 91 (Figs. 5 and 16) formed integrally therewith. To operate the arm 91 there is provided on the link 14 connecting the needle cam lever with the 85 needle segment, a pin 92 arranged to engage the upper end of an upwardly extending arm 93 forming part of a lever fulcrumed on a stud 94. This pin is adapted to engage the arm 93 as the connecting link 14 is 90 drawn rearwardly to throw the needle forward, and is so placed on said connecting link that it will engage the arm 93 during the first part of the forward movement of the needle. The arm 93 has a downwardly 95 extending arm 95 formed as a cam which is moved forwardly to engage and push downwardly the rear end of arm 91 as the arm 93 is moved rearwardly. The channel closing finger 80 is by such means moved to a 100 position out of engagement with the channel flap, and is held in such position during the remainder of the advancing stroke of the needle and also during such part of the retracting stroke of said needle as the pin 92 105 holds the cam 95 in engagement with said arm 91. A torsion spring 96, one end of which engages a pin on the arm 93 and the other end of which is connected to an arm rigid with the stud 94 tends to hold the cam 95 110 out of engagement with the arm 91, its movement under the force of the spring being determined by an abutment pin 97.

The channel guide (Fig. 6) is indicated 115 at 98 and, as shown, is secured to an arm 99 depending from the feed slide 100, which is mounted to reciprocate laterally and rock on the fixed feed slide stud 69 secured in the machine frame. The channel guide is moved toward and away from the shoe as 120 the feed slide is rocked about the stud 69. The rocking motion is accomplished through mechanism which will be hereinafter more particularly described.

The feed slide is reciprocated by means 125 of a lever 102 (Figs. 4 and 6) fulcrumed on a stud 103 having a roll 104 on its rear end, which engages a lateral cam groove 105 in the peripheral surface of one of the cams on the main shaft. The lever 102 is 130

provided with a slot 106 in which is adjustably secured a pin 107 having mounted therein a block 108 engaging in a slot in a bracket secured to the feed slide by screw 110. To enable the feed slide to be adjusted laterally in order to bring the awl into alignment with the needle at the end of the feeding movement, the portion of the stud 103 forming the fulcrum of the lever 102 is made eccentric to the axis of the stud and the stud is provided with a nut 111, by means of which it may be adjusted.

The means for imparting rocking movements to the feed slide 100 and arm 99 comprises a lever 112 splined at the forward end to a projection 113 extending from the right side of the feed slide. The lever 112 extends toward the rear of the machine, and at its rear end has a roll 114 engaging a cam groove in the vertical face of one of the driving cams secured to the main shaft. Intermediate its ends the sides of the lever 112 are flattened, and at such point it extends through a recess formed between two upstanding arms of a bracket 115 projecting from the frame and holding said lever against any lateral displacement.

The machine illustrated in the drawings is adapted for sewing turn shoes and consequently is provided with a back gage, for which a welt guide of ordinary construction would be substituted to adapt the machine for sewing welt shoes. So far as the present invention is concerned, a back gage and a welt guide are equivalents, and where the term "back gage" is used in the claims it is to be construed as including a welt guide or any other device which has the function of the back gage of an inseam shoe sewing machine. This back gage is indicated at 116 and is formed on the forward end of the back gage carrier 117. At its rear end the back gage carrier is pivotally connected to the lower end of an arm 118 projecting downwardly from the fulcrum stud 94, hereinbefore referred to in connection with the description of the flap closing finger 80. Midway between its ends the back gage carrier is provided with an inclined slot 119 through which passes a pin 120 journaled in ears projecting forwardly from a block or bracket 121 secured rigidly to the frame of the machine. The back gage is adapted to move towards and from the shoe, and on account of the manner in which the back gage is supported by the arm 118 and the pin 120, the back gage moves in a path approximately closely the path of the needle. While the needle is penetrating the work the back gage is pressed yieldingly against the work, and prior to the withdrawal of the needle is locked rigidly in position. To cause the back gage to be pressed yieldingly against the work, the spring 96, hereinbefore referred to in con-

nection with the description of the flap closing finger 80, is connected to the arm 118. As has been described, the pin 92 on the needle actuating link 14 engages the arm 93 during the work piercing stroke of the needle and rocks the arm about the fulcrum stud 94. This puts tension on the spring 96 and rocks the arm 118 so as to force the back gage 116 against the work, the pressure of the gage against the work being at first light, and increasing until the needle reaches the limit of its piercing stroke. The back gage is now locked in position by mechanism to be hereinafter described, and remains locked during the retracting movement of the needle. As the needle retracts, the pin 92 on the needle actuating link 14 moves away from the arm 93, and thus relieves the tension on the spring 96. When the back gage is unlocked, therefore, it ceases to press against the work, and remains either resting lightly on the work or in close proximity to the work.

The back rest, or bunter, is indicated at 122, and is shown as in the form of a roll supported at the forward end of a back rest slide 123. This slide is mounted in a guideway in the bracket 121 and is pressed towards the shoe by a spring pressed arm 124 journaled at its lower end in the frame of the machine and having its upper end in engagement with the rear end of the slide. The slide is guided in the bracket 121 by guiding pieces 125 which engage grooves formed in the sides of the slide and in the bracket 121 and which are held in place by screws 126. The back rest, or bunter, 122 is locked against backward movement and unlocked at the same points in the cycle of operations at which the back rest 116 is locked against backward movement and unlocked. The same mechanism is used to lock and unlock both the back gage and the back rest and this mechanism is arranged to act upon the slide 123 and upon a slide 127 connected to the back rest. The slide 127 is mounted in the bracket 121 and rests upon the upper surface of the back rest slide 123. It is connected to the back gage 116 by means of a link 128 extending between the lower end of the arm 118 and a lug 129 projecting upwardly from the slide. To lock the slides 127 and 123 against backward movement a locking bar 130 is provided having a rectangular opening at its upper end through which the slides pass. The upper and lower surfaces of the opening in the bar 130 are bevelled slightly at their edges as indicated in Fig. 18, and the bar is arranged at right angles to the slides in such a position that a tilting movement of the bar will force the two slides together and lock them against backward movement with relation to the locking bar. The upper end of the locking bar is received in a re-

cess in a slide 131 rigidly secured to the bracket 121 so that the upper end of the bar is held against movement with relation to the bracket and when the bar is actuated to grip the slides the slides are locked rigidly against backward movement with relation to the bracket. The lower end of the locking bar 130 is engaged by a spring pressed plunger 132 which forces the bar in a direction to hold a cam roll 133 at the lower end of the bar in contact with a cam 134 on the cam shaft of the machine. The plunger 132 at its end remote from the locking bar is mounted to slide in the hub of a screw 135 mounted in the bracket 121, and at the end which contacts with the locking bar is provided with a head between which and the hubs of the screw 135 its actuating spring 136 is located. The arrangement of the locking bar 130, the spring pressed plunger 132 and the cam 134 is such that movement of the lower end of the bar by the cam against the action of the spring pressed plunger unlocks the slides 123 and 127, while a movement of the lower end of the locking bar under the influence of the spring pressed plunger locks the slides. The locking movement of the locking bar takes place at that point in the cycle of operations at which the needle reaches the limit of its piercing stroke, while the unlocking movement of the bar takes place after the needle has completed its retracting movement and after the take-up has made its thread delivering movement to relieve the strain of the thread on the work during the feed. The slide 131 which engages the upper end of the locking bar 130 is mounted in a guide-way in the upper portion of the bracket 121 and has rigidly secured thereto a laterally projecting arm 137. The outer end of this arm is slotted and receives the head of an adjusting screw 138 mounted in a projection from the bracket 121. By means of this construction the upper end of the locking bar 130 can be adjusted so as to cause the locking bar to act to the best advantage.

The pin 120 which passes through the slot 119 in the back gage carrier is mounted in the ears of the bracket 121 by end portions which are eccentric to the center portion so that by rotating the pin a vertical adjustment of the back gage carrier and of the back gage can be secured as may be desired. A set-screw 139 serves to lock the pin 120 in adjusted position.

The machine illustrated in the drawings is provided with devices for withdrawing the back gage to a position out of engagement with the shoe when the machine is stopped. On the rod 86 which is operated from the starting and stopping treadle there is secured a cam 148 (Figs. 7 and 16) which, as the rod 86 rises, engages a pin 149 on an arm 150 secured to the left end of the stud

94, on the other end of which the arm 118 operating the back gage is secured. By this means the rod 86, as it rises after the release of the treadle, causes the arm 150 and consequently the arm 118 to move rearwardly, and withdraw the back gage from the shoe.

The tension wheel over which the thread is passed in the usual manner is indicated at 151 and as shown is secured to a plate 152 fastened on a short shaft 153 journaled at 154 in a bearing in the machine frame. In order to provide proper tension on the thread the rotation of the shaft 153 carrying the tension wheel is opposed by a brake 75 comprising a brake hub 155 integral with the shaft 153 and over which passes a brake strap or shoe 156, as shown in Fig. 7. The brake strap is a flexible band, one end of which is secured to a pin on the rear end of a lever 157 pivoted on a stud 158 and having an upstanding arm 159, to which is pivoted a rearwardly extending lever 160, on the rear end of which is a pin to which the other end of the brake strap 156 is secured. Adjustably secured in a bracket 161 projecting from the lever 157 is a rod 162 extending upwardly therefrom, and having surrounding it at its upper end a helical compression spring 163. This spring is confined between a collar 164 secured to the upper end of said rod and a similar collar 165 slidable on said rod and engaging on its lower side a lug 166 formed on the lever 160. When the machine is stopped the levers 157 and 160 and the brake strap 156 assume the position shown in Fig. 7 in which position the brake strap rests lightly on the brake hub 155 so that there is substantially no tension on the thread. When the machine is started the brake strap is pressed against the brake hub and held in firm contact therewith in order to apply tension to the thread during the sewing operation. To accomplish this result the rear end of the lever 157 is provided with an upturned portion 167 arranged to be engaged by a cam 168 formed on the lower side of a gear sector 169 mounted on the machine frame and pivotally connected to an upward extension of the rod 86. When the lever 157 is depressed by the engagement therewith of the cam 168 the brake strap 156 is forced into engagement with the brake hub 155, and is held in engagement therewith by a force equal to the strength of the spring 163.

To prevent the take-up in its operation during the formation of the first stitch from either pulling the thread out of the thread holding device to be hereinafter described, or breaking the thread, means are provided to rotate the tension wheel through a certain degree of movement whenever the machine is started. In order to give such rota-

tion to the tension wheel the rod 86, connected to the starting treadle, has at its upper end a flat extension, in which is a slot 170 through which passes a pin 171 secured to the gear sector 169 pivoted on a stud 172 and engaging with a gear 173 loosely mounted on the tension wheel shaft 153. In order that a rotation of gear 173 may rotate the tension wheel when the rod 86 is depressed there is provided a hub 174 integral with and extending to the right of gear 173 (Figs. 8 and 9). Keyed to the hub is one member 175 of a roll clutch, the other member of said clutch being the brake hub 155 fastened on said shaft 153 as above described. Lying in recesses 176 of said clutch member 175 are rolls 177 normally pressed by springs 178 into such position that a rotation of the clutch member 175 in one direction will cause the rolls to wedge between the clutch member 175 and the inner surface of the brake hub 155, in this manner causing the brake hub to rotate with the clutch member 175. The brake hub being integral with the shaft 153 will cause said shaft to be rotated and rotate the tension wheel. The construction of the clutch, however, is such that when the member 175 is rotated in the opposite direction the rolls 177 pass freely over the inner surface of the brake hub 155 and cause no rotation thereof. As stated previously, the treadle rod 86 when depressed to rotate the tension wheel in the manner described also lowers the lever 157 and causes the brake to be applied, thus applying tension to the thread and at the same time preventing any over-rotation of the tension wheel.

The movement of the gear sector 169 by means of rod 86 may be varied and by varying the amount of movement of such gear sector the movement of the tension wheel may be varied. To so adjust the movement of the gear sector there is provided in the extension of rod 86 a screw 179 the lower end of which projects into the slot 170 and strikes against the pin 171. This screw may be adjusted to vary the amount of lost motion provided by the pin and slot connection 170—171, in this manner varying the throw of the gear-sector, and consequently the rotation given to the tension wheel.

Devices are provided in the machine herein illustrated for cutting and holding the thread at the completion of the sewing. These devices are timed to operate so as to cut off the thread during the last cycle of operation of the stitch forming devices and to hold the end of the thread leading to the supply until the machine is again set into operation. The machine is also provided with a stop mechanism which, in cooperation with the thread cutting devices, stops the machine with the needle in retracted position free from the thread.

The devices for cutting and holding the thread comprise thread holding jaws 180 and 181 and a thread cutting knife 182. The thread holding jaws and knife are all mounted on the lower end of a lever 183, the thread holding jaws being arranged to slide in a guideway formed in the laterally projecting end 184 of said lever. The knife 182 is secured in the end of said lever by means of a bolt 185 and has no sliding movement. The thread holding jaws are, however, advanced by mechanism, to be herein-after described, out beyond the cutting edge of the knife, to grip the thread and are then retracted with the thread held between them. In this manner the thread is pulled across the edge of the knife which severs it and the thread is afterward held until the machine has been again started into operation.

During the operation of the machine in sewing a seam the lever 183 carrying the thread gripping jaws remains stationary at a considerable distance to the right of the plane of the needle but while the machine is being stopped, the lever is swung over to a position where the thread gripping jaws can grip the thread and is then moved back toward normal position with the thread held by said jaws. The lever 183 is pivoted on a stud 186 the end portions of which are eccentric to the center portion and about which the lever is adapted to swing freely. On an arm 187 of said lever is secured a pin 188 which engages a slot 189 in the end of an arm 190 secured to the forward end of a rock shaft 191 journaled in the framework of the machine and extending from the front to the rear of the machine. Also secured to said rock shaft midway between its ends is an arm 192 which has in its end a slot 193 engaging a pin 194 mounted on the depending end of a curved lever 195 which is pivoted at its other end on a stud 196 secured in the frame at the right side. Secured to the rear end of the rock shaft 191 is an arm 197 having a hole in its outer end in which is secured one end of a tension spring 199, the other end of which engages in a screw-eye 200 secured in the frame, said spring normally tending to pull the arm 197 to the left in Fig. 10. As stated above, the arms 190, 192 and 197, are all fast on the rock shaft 191 and rotate therewith, hence if the arm 197 is drawn to the left by its spring 199 the shaft 191 is rocked and the arms 190 and 192, swing downwardly. When the shaft 191 is so rocked the parts assume the position shown in Fig. 10 and the lever 183, is swung from a position where the thread gripping jaws are to the right of the thread to the position illustrated in said Fig. 10, where the thread lies between the thread gripping jaws 180 and 181.

The rocking of the shaft 191, by means

of the spring 199 to move the lever 183, as described, is controlled by a cam 201 loose on said shaft, the rotation of which cam is controlled in a manner hereinafter described. The peripheral surface of the cam 201 has several different levels or points of elevation indicated at A—B—C—D—E—F, which govern the movement and operation of the thread cutting and holding devices. 5 During the sewing of a seam this cam 201 is held in such a position that its highest level A engages a roll 203 pivotally mounted on a stud 202 secured to the lever 195 at a point midway between its ends. As the 10 machine is being stopped at the completion of the sewing operation the cam 201 is rotated in a clockwise direction so that the point A of said cam passes out of engagement with the roll 203 which is immediately 15 pulled down by spring 199 through the medium of arms 197, 192 and the shaft 191 until the roll 203 engages the surface of the depression B of said cam. The sliding jaw 180 has pressing against its right end a 20 leaf-spring 205 secured to the arm 183, which at all times tends to move the jaw towards the left, said jaw being provided also with a lug 206 at its right end which strikes against the arm 183 and limits the 25 leftward movement of said jaw. The jaw 181 has secured thereto a pin 207 which extends through a slot 208 in the end of the arm 183 and which is embraced by the bifurcated end of a lever 209 30 fulcrumed intermediate its ends on a pin 210 secured to the arm 183. To a pin 211 on the upper end of lever 209 is secured one end of a tension spring 212 the other end of which is secured to a pin 213 on the 35 arm 183, said spring always tending to rotate said lever 209 on its pivot and move the gripper jaw 181 to the right. The slot 208 through which the pin 207 extends, limits the movement of the jaw 181 and permits 40 said jaw to have substantially twice the sliding movement of the jaw 180. As arm 183 swings to the left, when the roll 203 drops into the depression B of cam 201, the upper end of the lever 209 is carried toward 45 the left and during such movement engages a latch 214, the lower end of which strikes against the left side of the upper arm of the lever 209, and rotates said lever around its pivot, thus moving the lower end of the lever 50 to the left relative to the arm 183. The latch 214 is pivoted on a stud 215 on the machine frame and has an upper arm which engages an abutment screw 216 secured in a projection extending from the frame, and 55 against which the latch is normally held by a torsion spring 217 surrounding the stud, one end of which spring is secured to the latch and the other to the frame. As the arm 183 swings to the left the lever 209 is moved by 60 the mechanism described from a position such as shown in Fig. 8 to that shown in Fig. 10. As the lever 209 is moved in this manner it slides the gripper jaw 181 to the left through a distance equal to the length of the slot 208, said movement of the gripper jaw 181 permitting jaw 180 to be moved to the left by its spring to a distance about one-half as great as that through which the jaw 181 is moved. Such movement leaves 65 a space between the jaws into which the thread passes. As the arm 183 reaches the limit of its downward movement the lever 209 passes beyond the latch 214 and the upper arm of said lever is snapped to the left by the spring 212. This action, through the 70 medium of the bifurcated lower arm of the lever and the pin 207, gives the jaw 181 a quick movement to the right, said jaw during such movement first clamping the thread against the jaw 180 and then moving the 75 jaw 180 back against the pressure of spring 205 until the pin 207 is in the right end of the slot 208, during which movement the thread is pulled across the knife edge and 80 severed. 85

As stated hereinbefore, the cam 201 has several points or levels of different height which control the movements of the thread cutting and holding devices. These different heights of the cam act to control the 90 operation of said thread cutting and holding devices in the following manner. The cam as previously stated normally occupies such a position when the machine is in operation that the highest point A engages the roll 203, holding the arm 183 which carries the thread cutting and holding devices in its position farthest toward the right. When the cam is tripped into operation it is rotated in a clockwise direction, and during 95 the first part of its motion is moved to such a position that the roll drops into the depression B, causing the thread cutting and holding devices to move to the left in the manner previously described. On further rotation of the cam the roll 203 is raised by the point C of the cam, which causes the thread cutting and holding devices to be moved to the right to the position shown in Fig. 8, 100 with the thread cut and the end of the thread held between the gripper jaws. This level C of the cam extends substantially concentrically for some distance and the machine is adapted to come to rest with the roll 203 engaged by some part of this eccentric surface. During the movement of the arm 183, caused by the movement of the cam 201 from a position where the roll 203 engages the depression B to a position where said 105 roll engages the level C, the latch 214 again snaps behind the upper arm of lever 209 as shown in Fig. 8, and when the machine comes to rest it occupies such position. When the machine is started to make its first 110 stitch forming operation, the thread is held 115

120

125

130

by the thread holder in such position that it will not be engaged by the thread arm, and the loop for the first stitch is laid in the barb of the needle by the action of the looper 5 alone. Accordingly, a slight depression D is provided on the cam 201, which comes into engagement with roll 203 subsequent to the starting of the machine at a time when the looper is about to loop the thread about 10 the needle. When such depression engages the roll 203 the arm 183 is permitted to move a certain distance to the left to give up the thread to the looper in its looping operation. Immediately after the depression 15 D is engaged by the roll 203 the continued rotation of the cam brings the higher point E of said cam into engagement with the said roll, said point E causing the arm 183 to be swung to the right in order to tighten 20 the loop about the shank of the needle. The needle then begins its retracting stroke and during such stroke the cam 201 continues to rotate until the point F engages the roll 203. The height of the cam between the points 25 E and F gradually becomes less so that the arm 183, as the cam continues its rotation, is permitted to move gradually to the left to give up the thread to the needle during its retracting stroke. When the point F comes 30 into engagement with the roll 203 the needle is making its second piercing stroke and point F is of such a level that the arm 183 is moved so far toward the left that the latch 214 engages and swings the lever 209 sufficiently to open the thread gripping jaws 35 and release the thread. After this action takes place, the cam continues its rotation until the point A of the cam engages roll 203, at which time the cam is brought to a stop by mechanism which will be hereinafter 40 more fully described.

The cam 201 is driven from the main shaft of the machine indicated at 218, which has on its right end a worm-gear 219 engaging a gear formed on a vertical shaft 220 journaled in bearings on the machine frame and having at its upper end a bevel gear 221 engaging a bevel gear 222 rotatably mounted on the shaft 191 on which said cam 45 is also free to rotate. These gears are so proportioned that gear 222 makes one-half of a revolution during each complete revolution of shaft 218. The gear 222 has a clutch member 223 formed integral therewith. 50 The cam 201 is secured for rotation with a sleeve 224 rotatably mounted on the shaft 191, the rear end 225 of the said sleeve being substantially square, as shown in Fig. 14, and constituting a clutch member which 55 operates with clutch member 223, so that when the clutch formed by these two clutch members is closed cam 201 is rotated by the main drive shaft. The square sides of the interior clutch member 225 form recesses 60 between said member and outer clutch member 223, in which recesses fit rolls 226. These rolls are arranged in pairs and are connected by compression springs 227, constantly tending to spread the rolls of each pair apart. Extending between the two pairs of rolls and limiting their motion under the action of springs 227 are lugs 228 projecting rearwardly from a collar 229 surrounding a portion of the sleeve 224. The collar 229 is adapted to be held stationary during the operation of the machine by means of a latch 230 which is adapted to be released in the manner hereinafter described, when the machine is stopped, and which engages a shoulder 231 of the collar 229. The function of the collar 229 and its projecting lugs is to hold the rolls of the clutch in such position that when the interior clutch member is stationary and the exterior clutch member is rotated during the operation of 70 the machine, the rolls will not be jammed between the clutch members. During the operation of the machine the interior clutch member is held against rotation by a latch 232 which engages a notch 233 formed in the peripheral surface of a flange integral with the sleeve 224. When the latch 230 engages the shoulder 231 and latch 232 is in the notch 233 the parts are in such a position that the outer clutch member 223 may be rotated, and during such rotation there is not sufficient friction to cause the rolls 226 to jam between the two clutch members. When, however, latches 230 and 232 are moved to 75 release the collar 229 and sleeve 224 the rolls jam between the inner and outer clutch members and the cam 201 is rotated with the gear 222. The latches 230 and 232 are moved to their releasing position through the medium of the starting and stopping treadle 80 when such treadle is moved to a position to stop the machine. To this end the latch 230, as constructed, forms one arm of a bell-crank lever pivoted on a stud and having an upper arm 234 pivotally connected at its 85 upper end to a link 235 which extends across the machine, where it is pivotally connected to an arm 236 of a lever pivoted at 237 in a projection extending from the machine frame. This lever has an arm 238 extending through an aperture in the middle plate of the machine frame and having an offset and forwardly projecting end lying in the path of, and adapted to be struck by, the head of a bolt 240 adjustably mounted on the rod 90. It will be readily understood from this description that as the rod 86 rises during the stopping of the machine the lever arm 236 is moved to the right in Fig. 8, and through link 235 rocks the bell-crank lever 234, thus raising the latch 230 out of engagement with the shoulder 233. The latch 232 is raised out of engagement with the notch 233 as latch 230 is raised, said latch 232 being pivoted on a stud 241 projecting 95

from the latch 230 and having a hole 242 therein which is engaged by a pin 243 extending laterally from the latch 230. A leaf-spring 244 tends to hold said latch 232 in engagement with the notch 233.

When the rod 86 rises and causes the closing of the clutch for actuating the thread holding and cutting devices, it also releases the arm 157 of the tension brake, allowing the said arm to rise and assume such a position that the tension is released. By means of such construction, when the thread cutting and holding devices are actuated to pull the thread to the right as in Fig 8, the thread is relieved of tension.

In the machine illustrated in the drawings the cutting of the thread takes place just after the looper has placed the thread in the hook of the needle, the thread gripping jaws engaging the thread, at this point in the cycle of operations, between the needle and the looper, as indicated in Figs. 10 and 11, and immediately withdrawing to the position indicated in Fig. 8. During the withdrawal of the thread gripping jaws to the position indicated in Fig. 8 the movements of the other parts of the machine are continued until the needle has been withdrawn from the work, at which time the driving shaft of the machine comes to rest. During the withdrawal of the needle the loose end of thread leading to the work is freed from the hook of the needle so that the work can be immediately removed without further manipulation of the machine or the work by the operator. To cause the cam 201 to be tripped into operation at the desired time in the cycle of stitch forming operations and the machine to be stopped after the thread cutting operation with the needle out of the work, the machine is provided with mechanism which may be described as follows:

The cam or driving shaft 218 of the machine is driven by means of a friction clutch face 245 formed on a clutch member 246 which is splined on the cam shaft. This clutch member also carries a friction brake face 247. With the parts in the position shown in Fig. 21 the brake face 247 is in engagement with a braking face 248 on the interior of the frame of the machine, and the cam shaft is at rest. To start the cam shaft into operation the clutch member 246 is moved toward the right to bring the clutch face 245 in engagement with a cooperating clutch face 249 on a constantly driven driving pulley 250. This driving pulley is mounted to turn loosely on a fixed bushing 251 surrounding the cam shaft, and is provided with a hub 252 adapted to engage a roll thrust bearing 253 when the driving pulley is forced toward the right by the engagement of the clutch faces 245 and 249. The clutch member 246 is pro-

vided with a grooved collar which is engaged by a clutch shifting yoke 254 pinned on a horizontal shaft 255. The shaft 255 is provided with a horizontally extending arm 256 to which is connected the treadle rod 300. The depression of the treadle rod 300 moves the clutch member 246 to the right to engage the clutch faces 245 and 249, and when the treadle is released a spring acting on the rod 300 tends to move the clutch member 246 to the left to bring the brake surface 247 into operation. After the treadle is released by the operator the movement of the clutch member 246 is controlled by two cams, both of which are formed on the hub of the hand wheel 257 which is fast on the cam shaft. When the starting treadle is depressed to move the driving clutch faces into engagement, a projection 258 on the shaft 255 is moved upwardly, so that a lug 259 on the depending arm of a latch lever 260 pivoted at 261, is drawn beneath the lug by spring 262 attached to the lower end of the latch lever and locks the rock shaft 255 against a sufficient backward movement to entirely disengage the driving clutch faces. The latch lever 260 is engaged by one of the cams on the hand wheel 257 during each revolution of the cam shaft, so that at a certain point in each cycle of operations of the machine the rock shaft 255 is released, and unless held by the operator, through the medium of the foot treadle, can move in a direction to disengage the driving clutch faces. This cam is indicated at 263. While the machine is running there is sufficient play between the lug 259 on the latch 260 and the lug 258 on the shaft 255 to allow the driving clutch to be so controlled by the operator through the foot treadle as to vary the speed of the cam shaft. When the operator takes his foot off the treadle the rod 300 rises and rocks the shaft 255 so that the lug 258 engages the lug 259, but at this time there is sufficient friction exerted between the driving clutch faces to drive the cam shaft so that the cam shaft continues to rotate after the operator takes his foot from the treadle until the latch lever is operated by the cam 263. The operation of the latch lever releases the rock shaft 255 and allows the clutch member 246 to move further towards the left, so as to entirely disengage the driving clutch faces. The cam shaft now continues to rotate under its own momentum. At this time the braking surface 247 is held out of engagement with the cooperating surface on the frame. The clutch member 246 is controlled at this stage in the operation by means of the second cam 264 on the hub of the hand wheel 257, which cam is engaged by a roll 265 on the upper end of an arm 266 adjustably but rigidly secured on the clutch operating yoke 254. At a certain point in the rotation of

the cam shaft, and a predetermined number of degrees of rotation after the cam 263 has operated to release the latch through lever 260, the cam 264 allows the clutch member 246 to move so as to bring the braking surface 247 against the machine frame.

A coiled spring 365 surrounds the hub of the driving pulley 249 and is interposed between the web of the pulley and the 10 thrust bearing 253. The function of this spring is to keep the driving clutch faces in engagement after the operator releases the treadle, and until the latch lever 260 is operated. The movement of the driving pulley 15 to the left under the action of the spring 365 is limited by a stop collar 366.

The rod 86, upward movement of which trips the thread cutting and holding devices into operation, is pivotally connected 20 at its lower end to the arm 256. Since this arm is rigidly connected through the shaft 255 to the clutch shifting yoke 254 its movements and consequently the movements of the rod 86 are controlled by the cams 263 and 264 on the hand wheel in the same 25 manner as the movements of the clutch shifting yoke. The first slight upward movement of the rod 86, which takes place when the foot treadle, connected to the rod 300, is released by the operator, and which is limited by the engagement of the lug 258 on the shaft 255 with the lug 259 on the latch 260, is not sufficient to trip the thread cutting 30 and holding devices into operation. The 35 movement of the rod 86 which takes place when the latch 260 is actuated by the cam 263, however, is sufficient to trip the thread cutting and holding devices into operation. This movement, being timed by the cam 263, 40 occurs at a predetermined point in the stitch forming cycle of the machine, which point, in the machine illustrated, is such that the thread is engaged and cut just after the thread has been placed in the needle hook by the looper. The low point in the 45 cam 264, which allows the braking surface 247 to stop the machine is so located that the driving shaft comes to rest with the needle in retracted position out of the work.

To enable the thread handling devices of the machine to be properly heated the 50 machine frame is formed with a central plate 267, and extending from the front to the back of the machine and adjacent said frame plate there is provided a steam tube 268 connected at its ends to steam pipes 269 and 270 to conduct steam through said tube from a suitable steam supply. The steam pipe 269 extends through the frame casting at a 55 point adjacent the thread tube and said tube is secured at one end in a projection formed on the central plate, so that by means of the steam pipes described the thread tube and the central plate of the frame are heated to 60 a high degree. The main take-up operates

in a slide guide formed in the heated central plate. The auxiliary take-up is pivoted on a stud secured in said central plate, and the thread arm is pivoted on a stud secured in said plate on which stud the channel 70 guide slides. The take-up, auxiliary take-up, thread arm and channel guide are thus all heated by conductivity from the heated central plate, as is also the thread tube. The looper actuating devices are also arranged so as to extend through a bracket projecting from said heated plate and the looper therefore is heated by direct conduction from said plate.

A machine embodying the several features 20 of the present invention in their preferred form having been specifically described, what is claimed is:

1. A shoe sewing machine, having, in combination, a curved hook needle, a needle 25 guide for said needle, needle actuating means for advancing and retracting the needle and a cam operated by said needle actuating means for advancing and retracting said needle guide.

2. A shoe sewing machine, having, in combination, a curved hook needle, a needle 30 guide for said needle, needle actuating means comprising a cam lever for advancing and retracting the needle, a lever having a 35 cam therein for advancing and retracting the needle guide; and actuating connections between said lever and the needle actuating cam lever.

3. A shoe sewing machine, having, in combination, stitch forming devices including 40 a hook needle and a thread arm, a cam shaft and suitable connections for advancing and retracting the needle, and means actuated by said connections for oscillating the 45 thread arm.

4. A shoe sewing machine, having, in combination, stitch forming devices including a hook needle and a thread arm, needle 50 actuating means including a cam lever for advancing and retracting the needle, and a cam actuated by the needle cam lever for oscillating the thread arm.

5. A shoe sewing machine, having, in combination, stitch forming devices including a hook needle, a thread arm and a needle 55 guide, a cam shaft and suitable connections for advancing and retracting the needle, and means actuated by said connections for operating the thread arm and needle guide.

6. A shoe sewing machine, having, in combination, stitch forming devices including a hook needle, a thread arm, a needle guide, needle actuating means for advancing and retracting the needle and including an oscillating cam lever, and means for operating the thread arm and needle guide, comprising a lever actuated from the needle cam lever and having two cams formed therein.

7. An inseam shoe sewing machine, hav-

- ing, in combination, a hook needle, needle actuating means for advancing and retracting the needle, a back gage, a spring for moving the back gage into engagement with the work normally under no tension, and means for gradually increasing the tension of the spring. 65
8. An inseam shoe sewing machine, having, in combination, a hook needle, needle actuating means for advancing and retracting the needle, a back gage, a spring for moving the back gage into engagement with the work normally under no tension, and means controlled by said needle actuating means for gradually increasing the tension of the spring. 70
9. An inseam shoe sewing machine, having, in combination, a hook needle, needle actuating means for advancing and retracting the needle, a back gage, a spring for moving the back gage into engagement with the work, means operated by the needle actuating means during the advancing stroke of the needle to gradually increase the tension of said spring to advance the back gage, said means acting during the retracting stroke of said needle to decrease the tension on said spring. 75
10. An inseam sewing machine, having, in combination, a hook needle, needle actuating means for advancing and retracting the needle, a spring normally under no tension, means for gradually tensioning the spring to move the back gage into engagement with the work, means for locking the back gage in work engaging position, means for operating said tensioning means to relieve the spring of tension tending to advance the back gage while the back gage is locked, and means for thereafter releasing the locking means. 80
11. An inseam shoe sewing machine, having, in combination, stitch forming devices, a channel flap closing device, and means for pressing the channel flap closing device, yieldingly against the work. 85
12. An inseam shoe sewing machine, having, in combination, stitch forming devices, a channel flap closing device, and means for moving said device yieldingly into engagement with the work and out of engagement therewith during each cycle of the stitch forming devices. 90
13. An inseam shoe sewing machine, having, in combination, stitch forming devices, a channel flap closing device and means for moving said device into and out of engagement with the work during each cycle of the stitch forming devices, acting to hold the channel flap closing device out of engagement with the work while the needle is in the work. 95
14. An inseam shoe sewing machine, having, in combination, stitch forming devices including a needle, needle actuating means, a channel flap closing device, yielding means for moving said device into engagement with the work, and means operated by the needle actuating means for moving said channel flap closing device out of engagement with the work. 100
15. An inseam shoe sewing machine, having, in combination, stitch forming devices, a channel flap closing device, and means operated on stopping the machine to move said channel flap closing device out of engagement with the work. 105
16. An inseam shoe sewing machine, having, in combination, stitch forming devices, a channel flap closing device, stop mechanism for stopping the machine on completion of the sewing, and means controlled by said stop mechanism to move said channel closing device out of engagement with the work. 110
17. An inseam shoe sewing machine, having, in combination, stitch forming devices including a needle, a channel flap closing device, means for actuating the needle, and means operated by said needle actuating means during each cycle of the stitch forming devices for moving the channel flap closing device to a position where it does not engage the channel flap. 115
18. A shoe sewing machine, having, in combination, a curved hook needle, a thread arm acting to measure off thread between the work and the needle, a looper, a take-up acting to exert a stitch-setting strain on the thread when the needle is in the work, and means for actuating the needle, thread arm and looper to form a chain stitch, the loop of which is twisted through a complete turn. 120
19. A shoe sewing machine, having, in combination, a curved hook needle, a thread arm acting to measure off thread between the work and the needle, a looper, a take-up acting to exert a stitch-setting strain on the thread while the needle is in the work, means for causing the looper to encircle the needle by a movement passing first outside of the circle of the needle and then inside of the circle of the needle, and means for moving the thread arm to a position in which the thread is held out of the needle hook until the looper has moved inside of the circle of the needle. 125
20. A shoe sewing machine, having, in combination, a curved hook needle, a thread arm acting to measure off thread between the work and the needle, a looper, a take-up acting to exert a stitch-setting strain on the thread while the needle is in the work, means for causing the looper to encircle the needle by a movement passing first outside of the circle of the needle and then inside of the circle of the needle, and means for moving the thread arm outwardly towards the center line of the shoe to a position in which

the thread is held out of the hook of the needle until the looper has moved inside the circle of the needle.

21. A shoe sewing machine, having, in combination, a curved hook needle, a looper carrying slide, a supporting slide on which the looper carrying slide is mounted to move with the supporting slide and to have an independent transverse movement, and means for actuating the slides to cause the looper to place the thread in the hook of the needle.

22. A shoe sewing machine, having, in combination, a curved hook needle, a looper carrying slide, a supporting slide on which the looper carrying slide is mounted to move with the supporting slide and to have an independent transverse movement, a guide for the looper carrying slide pivotally mounted on the supporting slide, and means for actuating the slides to cause the looper to place the thread in the hook of the needle.

23. A shoe sewing machine, having, in combination, a hook needle, a looper, a take-up, a holder for the free end of the thread, devices for resisting the strain put upon the thread by the take-up, and means for supplying slack thread between said devices and the thread holder to relieve the strain on the thread holder during the first stitch forming cycle.

24. A shoe sewing machine, having, in combination, a hook needle, a looper, a take-up, a holder for the free end of the thread, devices for resisting the strain put upon the thread by the take-up, and means operated on starting the machine for supplying slack thread between said devices and the thread holder to relieve the strain on the thread holder during the first stitch forming cycle.

25. A shoe sewing machine, having, in combination, a hook needle, a looper, a take-up, a holder for the free end of the thread, a tension wheel over which the thread passes, and means for rotating the tension wheel to supply slack thread between the tension wheel and the thread holder during the first stitch forming cycle.

26. A shoe sewing machine, having, in combination, a hook needle, a looper, a take-up, a holder for the free end of the thread, a tension wheel over which the thread passes, a brake for the tension wheel, and means operated on starting the machine for applying the brake to the tension wheel and for rotating the tension wheel to supply slack thread between the tension wheel and the thread holder during the first stitch forming cycle.

27. A shoe sewing machine, having, in combination, work feeding and stitch forming devices including a curved hook needle and a looper operating to sew a continuous seam, and means acting automatically on stopping the machine to sever the thread and bring the needle to rest out of engagement with the work.

28. A chain-stitch shoe sewing machine, having, in combination, work feeding and stitch forming devices including a curved hook needle and a looper operating to sew a continuous seam, and means acting automatically on stopping the machine to sever the thread between the looper and the work and thereafter bring the needle to rest out of engagement with the work.

29. A sewing machine, having, in combination, stitch forming mechanism including a hook needle and looper, mechanism for stopping the machine at the end of the sewing, thread cutting and holding devices, and actuating mechanism for said devices rendered active upon the throwing in of the stop mechanism.

30. A sewing machine, having, in combination, stitch forming mechanism including a hook needle and looper, stop mechanism for stopping the machine at the completion of the sewing, thread cutting and holding devices and actuating mechanism for said devices controlled from the stop mechanism.

31. A chain-stitch shoe sewing machine, having, in combination, stitch forming mechanism including a hook needle and a looper, thread cutting and holding devices operating to sever the thread between the looper and the work and to hold the thread extending to the supply, stop mechanism, and means operating automatically when the stop mechanism is rendered active and before the machine is stopped to operate the thread cutting and holding devices.

32. A chain-stitch shoe sewing machine, having, in combination, stitch forming mechanism including a hook needle and looper, means for advancing and retracting the needle, stop mechanism rendered active when the needle is advanced and operating to bring the machine to a stop when the needle is retracted, thread cutting and holding devices, means operating the thread cutting and holding devices when the stop mechanism is rendered active and before the machine is stopped, whereby the thread is cut and held when the needle is in its advanced position and is freed from the needle when the needle reaches its retracted position.

33. A chain-stitch shoe sewing machine, having, in combination, stitch forming mechanism including a hook needle and looper, needle actuating means for advancing and retracting the needle, means for stopping the machine when the needle is in its retracted position, and means acting to cut and grip the thread when the needle is in its advanced position.

34. A shoe sewing machine, having, in combination, stitch forming mechanism including a hook needle and looper, thread cutting and holding devices, actuating

means therefor including a cam, and means for operating the cam upon stopping the machine.

35. A shoe sewing machine, having, in combination, stitch forming mechanism including a hook needle and looper, thread cutting and holding devices, a lever for actuating said devices, a spring for moving said lever in one direction, a cam for controlling the movements of the lever by said spring and moving said lever in the opposite direction, and means operated on stopping the machine for rotating the cam to a position to permit said lever to move the thread cutting and holding devices to operative position.

36. A shoe sewing machine, having, in combination, stitch forming mechanism, including a hook needle and looper, thread cutting and holding devices, means operating said cutting and holding devices to cut and hold the thread when the machine is stopped at the completion of the sewing, and means for operating said devices to release the thread after the machine is started.

37. A shoe sewing machine, having, in combination, stitch forming mechanism including a hook needle, a looper, thread holding devices holding the thread during the first cycle of operations, and means operating said thread holding devices while holding the thread to give up thread to the looper, during the first cycle of operations.

38. A shoe sewing machine, having, in combination, stitch forming mechanism including a hook needle, a looper, thread holding devices holding the thread during the first cycle of operation, means moving said thread holding devices to give up thread to the looper during said first cycle of operations and to tighten the loop about the needle.

39. A shoe sewing machine, having, in combination, stitch forming instrumentalities including a hook needle, a needle guide, an awl, a thread arm, a cam lever, and devices connected to said cam lever and operated thereby for actuating said needle, needle guide, awl and thread arm.

40. A shoe sewing machine, having, in combination, stitch forming mechanism including a hook needle, a thread arm and looper, thread holding devices for holding the thread in such a position during the first cycle of operations that it cannot be engaged by the thread arm, and means for operating said thread holding devices to give up thread to the looper during the formation of the first stitch.

41. A chain-stitch shoe sewing machine, having, in combination, a hook needle, a looper a main take-up acting to exert a stitch setting strain on the thread while the needle is in the work, a spring-pressed auxiliary take-up, a stop to limit the yielding move-

ment of the auxiliary take-up under the strain exerted on the thread by the main take-up, and means for moving the stop during each cycle of operations to permit a greater yielding movement under the strain exerted on the thread by the needle.

42. A shoe sewing machine, having, in combination, stitch forming devices including a hook needle, a main take-up, an auxiliary take-up, and means operated by the main take-up for raising the auxiliary take-up against the strain of the thread during the taking-up stroke of said main take-up and for holding said auxiliary take-up raised during the remainder of the taking-up stroke.

43. A shoe sewing machine, having, in combination, stitch forming devices including a hook needle, a main take-up, an auxiliary take-up, means for advancing and retracting the needle, a spring normally tending to move said auxiliary take-up in one direction, and means operated by said main take-up for moving said auxiliary take-up a predetermined distance in such direction during the taking-up stroke of the take-up.

44. A chain-stitch shoe sewing machine, having, in combination, stitch forming devices including a hook needle, a looper, and a take-up, means for feeding the work while the needle is out of the work, and means for retracting the take-up to give slack thread for the feeding movement.

45. A shoe sewing machine, having, in combination, stitch forming devices including a hook needle, a looper, and a take-up, means for feeding the work while the needle is out of the work, and means for retracting the take-up and simultaneously dipping the needle to give slack thread for the feeding movement.

46. A shoe sewing machine having, in combination, work feeding and stitch forming devices including a curved hook needle and a looper operating to sew a continuous seam, and means acting automatically on stopping the machine to engage and hold the thread between the looper and the work.

47. A shoe sewing machine having, in combination, work feeding and stitch forming devices including a curved hook needle and a looper operating to sew a continuous seam, and means acting automatically on stopping the machine to sever and hold the thread.

48. A chain-stitch shoe sewing machine having in combination, work feeding and stitch forming devices including a curved hook needle and a looper operating to sew a continuous seam, and means acting automatically on stopping the machine to sever 120 and hold the thread between the looper and the work.

49. A shoe sewing machine having, in combination, stitch forming mechanism including a hook needle, a looper, thread holding 130

devices holding the thread during the first cycle of operations, and means operating said thread holding devices to give up thread to the stitch forming mechanism during the 5 first cycle of operations.

50. A shoe sewing machine having, in combination, stitch forming mechanism including a hook needle and a looper, thread severing and holding devices, means for operating said severing and holding devices to sever and hold the thread when the machine is stopped at the completion of the sewing, a thread tension device, and means for releasing the tension on the thread during the 10 operation of the thread severing and holding devices.

51. A shoe sewing machine having, in combination, a curved hook needle, a looper, and mechanism for actuating the looper to 20 place a thread in the hook of the needle comprising two slides movable at an angle to each other and one of said slides being supported on the other.

52. A shoe sewing machine having, in combination, stitch forming devices including a hook needle, a looper and a take-up, means for feeding the work while the needle is out of the work, and means for dipping the needle to give slack thread for the feeding 25 movement.

53. An inseam shoe sewing machine having, in combination, stitch forming and work feeding mechanism for sewing the inseam of a shoe, and means for automatically severing the thread and for holding the thread 35 to start the inseam.

54. A shoe sewing machine having, in combination, stitch forming and work feeding mechanism for sewing a seam attaching 40 an upper to the sewing rib of the sole of a lasted shoe, and means acting on stopping the machine to sever the thread.

55. A shoe sewing machine having, in combination, work feeding and stitch forming devices including a curved needle operating to sew a seam attaching an upper to the sewing rib of the sole of a lasted shoe, and means acting on stopping the machine to sever the thread.

56. A shoe sewing machine having, in combination, a hook needle, a looper, a take-up, a holder for the free end of the thread, devices for resisting the strain put upon the thread by the take-up, and means for relieving the strain of the thread on the thread holder during the first stitch forming cycle.

57. A chain stitch shoe sewing machine having, in combination, a hook needle, a looper, a take-up acting to exert a stitch setting strain on the thread while the needle is in the work, a spring and suitable connections acting on the thread between the work and the supply, a stop to limit the yielding movement of said spring, and means for moving the stop during each cycle of operations to permit a yielding movement of the spring under the strain exerted on the thread by the needle. 60

58. A chain stitch shoe sewing machine having, in combination, a hook needle, a looper, a take-up acting to exert a stitch setting strain on the thread while the needle is in the work, a spring and suitable connections acting on the thread between the work and the supply, and means actuated during each cycle of operations for permitting a greater yielding movement of the spring under the strain exerted on the thread by the needle. 70

59. A chain stitch shoe sewing machine having, in combination, a hook needle, a looper, a tension, a take-up acting while the needle is in the work to exert a stitch setting strain on the thread against the tension and pull thread through the tension for the next stitch, a spring and suitable connections acting on the thread between the work and the tension, and means actuated during each cycle of operations for limiting the yielding movement of said spring during the action of the take-up and for permitting a yielding movement under the strain exerted on the thread by the needle. 80

60. A chain stitch shoe sewing machine having, in combination, a hook needle, a looper, a take-up acting to exert a stitch setting strain on the thread while the needle is in the work, a spring and suitable connections arranged to yield during the reTRACTING stroke of the needle, and means actuated during each cycle of operations for preventing said spring from yielding during the stitch setting action of the take-up. 100

61. An inseam shoe sewing machine having, in combination, a hook needle, needle actuating means for advancing and retracting the needle, a back gage arranged to rest lightly against the shoe, and means operating during each cycle of operations for pressing the back gage yieldingly with increased pressure against the shoe and for then locking it in position. 105

ALFRED B. FOWLER.
